UNITED STATES PATENT OFFICE.

HENRY H. VAUGHAN, OF MONTREAL, QUEBEC, CANADA.

LOCOMOTIVE DRAW-GEAR.

1,163,119.

Specification of Letters Patent.

Patented Dec. 7, 1915.

Application filed April 1, 1912. Serial No. 687,909.

To all whom it may concern:

Be it known that I, HENRY H. VAUGHAN, of Montreal, in the Province of Quebec and Dominion of Canada, have invented a certain new and useful Improvement in Locomotive Draw-Gear, of which improvement the following is a specification.

The object of my invention is to provide a simple and inexpensive means whereby the requisite relative movement of a locomotive engine and a tender coupled thereto, in passing to, through, and from curved portions of a railroad track, may be permitted, without impairment of the normal bearing of the two vehicles, one against the other, and, by the use of which, any slack which may be developed in the draw bar by which the locomotive and tender are connected, may be readily and fully taken up, as may, from time to time, become necessary or desirable.

The improvement claimed is hereinafter fully set forth.

In the accompanying drawings: Figure 1 is a plan or top view of the adjoining portions of a locomotive engine and tender, illustrating an application of my invention; Fig. 2, a vertical, longitudinal, central section through the same; and, Fig. 3, a longitudinal section through the chafing plate of the tender.

My invention is herein exemplified in connection with the draw gear of a locomotive engine and tender, comprising a draw bar, 1, coupled, in the usual manner, to the locomotive, by a pin, 2, passing through a pocket, 3^a, on the under side of the foot plate, 3, and coupled to the tender by a pin, 4, passing through a pocket, 5^a, secured to the front end sill, 5.

In the practice of my invention, a chafing plate, 6, of box form, the rear vertical wall of which is convex and curved substantially concentrically with the engine coupling pin, 2, is secured centrally to the rear of the foot plate, 3, by bolts passing through lateral flanges, 6^a, at its front. A chafing plate casing 7 of box form, the front side of which is entirely open, is secured centrally to the front end sill, 5, of the tender, by bolts passing through lateral flanges, 7^a, at its rear, and a chafing plate, 8, of box form, is fitted freely between its side walls, said plate being of substantially the same depth as the chafing plate, 6, of the locomotive, and being located in the same horizontal

plane. The front vertical wall of the chafing plate, 8, is convex and curved substantially concentrically with the tender coupling pin, 4, and inwardly extending bearing faces, 8^a, which are inclined, in line one with the other, to the longitudinal central plane of the tender, are formed at the rear ends of its side walls. The chafing plate, 8, is held in position in the casing, 7, with the capacity of a limited degree of longitudinal movement, by a vertical pin, 8^b, passing through longitudinal slots, 8^c, in the plate, 8, and secured by a split pin or cotter.

A chafing block, 9, is interposed between, and makes contact with, the curved walls of the chafing plates 6 and 8, its front and rear walls being concave, in correspondence with the convex curvature of the adjoining rear and front walls, respectively, of the chafing plates, 6 and 8. The chafing block, 9, is coupled to, and suspended on, the locomotive chafing plate, 6, by a hooked lug, 9^a, which is formed on its top, and fits in a slot, 6^b, in the top of the plate, 6, said slot being curved concentrically with the rear wall of said plate. A horizontal flange, 9^b, is formed on the bottom of the chafing block, 9, and projects therefrom below the bottom of the chafing plate, 6, in order to prevent the accidental displacement of the chafing block, 9.

Under the construction above described, it will be seen that the locomotive and tender are free to move laterally, relatively one to the other, in which movements the correspondingly curved adjoining faces of the chafing plates and the interposed chafing block, 9, remain in contact throughout the length of said chafing block, and consequently that the normal bearing of the locomotive and tender, one on the other, is maintained on curves as well as on tangents of the road, thereby correspondingly reducing the tendency to wear and lost motion of the draw bar and coupling pins.

One of the essential features of my improvement relates to the particular dimensions of the central chafing block which must be of sufficient length relative to its width between the chafing plates and its radius of curvature that the surfaces will engage each other over a comparatively long area, and the lateral thrust exerted by one of the chafing plates upon the chafing block when swinging on the opposite pivot of the draw bar will move said block radially upon

said surfaces without excessive friction or binding between the parts. The lateral movement of said block is thus effected solely by the pressure of the coöperating surfaces, as the vehicles swing laterally or turn at an angle to each other in passing around curves, the chafing block being otherwise free and having no connections with the draw bar or coupling pins. It will also be seen that the central chafing block has the capacity of relative movement with the engaging surfaces of both of said chafing plates whereby the wear due to the vertical vibrations, or the relative vertical movement between the adjoining ends of the respective vehicles, may be distributed upon both sides of the chafing block, thereby greatly increasing the flexibility and durability of the device, and this comprises another feature of my improvement.

In order to compensate for such wear of the coupling members as is unavoidable in service, by maintaining the surfaces of the chafing plates and chafing block in normal frictional contact, the chafing plate 8, may be moved outwardly, throughout the range permitted by the longitudinal slots, 8^c, by a transversely extending key, 10, which bears against the rear wall of the casing, 7, and the inclined bearing faces, 8^a, of the plate, 8, and is held in position, when adjusted, by a vertical bolt, 10^a, passing through one of a plurality of holes, 10^b, in the key, and through holes in the upper and lower walls 35 of the casing, and being secured by a split pin or cotter.

It will be obvious that the chafing block, 9, may, if preferred, be coupled to the chafing plate of the tender, instead of that of the locomotive as described and shown, and that such structural modification would involve no departure from the spirit and operative principle of my invention.

I claim as my invention and desire to secure by Letters Patent:—

1. In a draft gear for railroad vehicles, the combination of a draw bar pivotally connected at its ends to the respective vehicles, two chafing plates, each adapted for connection to the end of a vehicle, and having convex outer surfaces, and an interposed chafing block having double concave faces coöperating with the convex faces of the adjoining chafing plates, said block being independent of the draw bar, and having the capacity of relative vertical movement with the engaging surfaces of both of said chafing plates.

2. In a draft gear for railroad vehicles, the combination of two chafing plates, each adapted for connection to the end of a vehicle, and having convex outer surfaces, and an interposed chafing block having double concave faces coöperating with the convex faces of the adjoining chafing plates, said block having the capacity of relative vertical movement with the engaging surfaces of both of said chafing plates.

HENRY H. VAUGHAN.
